United States Patent Office.

WILLIAM HAMILTON, OF CHICOOPEE, MASSACHUSETTS.

Letters Patent No. 79,343, dated June 30, 1868.

IMPROVEMENT IN HOSE-COUPINGS.

The Schedule referred to in these Letters Patent and making part of the same.

TO ALL WHOM IT MAY CONCERN:

Be it known that I, WILLIAM HAMILTON, of Chicopee, Hampden county, Commonwealth of Massachusetts, have invented a new and useful Improved Hose-Coupling; and I do hereby declare that the following is a full and clear description thereof, reference being had to the accompanying drawings, and to the letters of reference marked thereon.

In the drawings—

Figure 1 is a plan view of one of the parts,

Figure 2 a side view of the whole, and

Figure 3 a detailed view of my invention.

This invention consists of a new and improved arrangement for a reversible-lock hose-coupling, and the same is constructed as follows:

Each part of my coupling is formed alike, so that a joint can be made with any two parts, and on each part is a bevelled rim, A, around the front outer edge; and upon one side of each part of the coupling this rim is turned over into a lip, B, the inner concave side of which corresponds to the rim A on the other part.

When the two parts are put together, the lip of each fits over the rim of the other, and thus a lock is made which prevents the possibility of the parts being forced asunder in the same line; and it only becomes necessary to clamp the parts in this position in order to complete the joint.

In order to accomplish this, I form on each part, opposite to the lip, and a short distance back of the rim A, a projecting block, C, fig. 3, in which is arranged a spiral slotted pin, D, having a bolt-head upon its end at E, the other end being intended to clamp upon the top of the lip B of the other part, and also against a projection, F, upon the lip; the pin D being outside of this projection, and thus preventing more perfectly the two parts of the coupling from being slipped apart.

In order that the pin shall jam at its end against the projection F, I form it at this part eccentrically to the body of the pin, so that when the pin is turned, the spiral slot H, guided upon the pin G, forces it down and clamps it against the top of the lip B, and the side of the eccentric end J against the projection F, the maximum of the eccentric being towards the projection at the time when the pin D is furthest down. The pin G, forming the guide for the slotted pin D, is put through the block C, and projects into the slot H as its guide.

The operation of this is as follows:

In putting the parts together, the two lips are put on opposite sides, and the rim of each slides under the lip of the other. The pins are then turned until they securely clamp against the lips.

A great advantage of strength is obtained by the curved form of these lips, as it requires a much greater strain to break one than would be required to break a straight one of the same stock; consequently they can be made much lighter.

The rest of the device is simple and perfectly reversible, so that any two parts can be joined at once without rearranging.

Having described my invention, what I claim as new, and desire to secure by Letters Patent, is—

The combination of the two parts of the coupling, each having a lip, B, and rim A, with the fastening-pin D, with spiral slot H and eccentric-face J, the parts being constructed and arranged together substantially as herein given.

WM. HAMILTON.
